GEORGE D. LAMBERT, OF NEW HAVEN, CONNECTICUT.

Letters Patent No. 100,642, dated March 8, 1870.

IMPROVEMENT IN CLAMPS.

The Schedule referred to in these Letters Patent and making part of the same.

To all whom it may concern:

Be it known that I, GEORGE D. LAMBERT, of New Haven, in the county of New Haven, and State of Connecticut, have invented a new and useful Improvement in Clamps; and I do hereby declare that the following is a full and exact description of the same, reference being had to the accompanying drawings and to the letters of reference marked thereon.

Figure 1 is a side view of my improvement.

Figure 2 is a longitudinal section of the same.

Figures 3 and 4 are detached views of the arm, to more clearly show its construction and operation.

This invention consists in providing the movable arm of an adjustable clamp with graduated teeth, for the purpose of giving the former a more perfect hold upon the latter.

To enable others skilled in the art to make and use my improvements, I will proceed to describe the construction and operation of the same, with reference to the accompanying drawings.

A is the beam of the clamp, provided at one extremity with a jaw, B. The outer edge of this beam is furnished with teeth, as shown in figs. 2, 3, and 4.

C is the adjustable arm, and D the short screw with which pressure is given to the block. The opening in the arm C, through which the beam A passes, is made tapering in shape, and upon its rear inside surface, serrations are placed, made deep at the bottom to correspond with those of the beam, but gradually diminishing in depth toward the upper end, until they die out entirely as shown in fig. 4.

Upon the opposite side of the beam A, a spring, E, is placed, operating upon the said beam, and let into the arm C in order to give it room to work. The object of this spring is to force and hold the teeth upon the beam A and arm C in their proper relative positions, and prevent any liability of its being permanently detached.

This completes the construction of my invention. The operation is as follows:

After the clamp has been placed upon the article, the arm C is pressed forward as far as possible, the spring E allows the serrations or teeth upon the arm to advance

over those upon the beam, so that this is easily and readily performed, and when left at any given point, the arm is held by the said spring and teeth firmly to the beam at that point. The remaining deficiency between the arm and the work is taken up, and the proper pressure given by means of the short screw D.

To enlarge the capacity of the clamp, the arm is forced downward, as shown in fig. 3. This contracts the spring E, and throws out or disconnects the teeth upon the arm from those upon the beam, and while held in this position, the said arm may be moved backward to any required point.

I am aware that the serrated beam has been used for this purpose, and I do not consider it a part of my invention in adjustable clamps. Where this beam is used, a plate, provided with corresponding serrations, is placed within the arm, and is operated upon the same by means of a nut or set-screw, this requiring nearly as much time and labor to prepare it for use as if it were not adjustable; and it is also objectionable from the fact that it is not certain. There may be cases where the points of the teeth would come together and prevent the plate from being secured into its place, and the moment pressure was put upon it, it would slip. In my improvement, the spring E prevents the liability of its slipping, and the graduated teeth upon the arm allow it to be readily moved backward in the manner before stated.

I do not claim a movable arm provided with teeth equal in size, for this I know to be old, but

Having thus fully described my invention, What I claim as new and useful, and desire to secure by Letters Patent, is—

The movable arm C, when provided with graduating-teeth, as shown and described, for the purpose set forth.

This specification signed and witnessed this 29th day of September, 1869.

GEORGE D. LAMBERT.
